UNITED STATES PATENT OFFICE.

JACOB A. MOLLER, JR., OF NEW YORK, N. Y.

DESIGN FOR A CUP.

SPECIFICATION forming part of Design No. 37,168, dated October 11, 1904.

Application filed September 14, 1904. Serial No. 224,475. Term of patent 7 years.

To all whom it may concern:

Be it known that I, JACOB A. MOLLER, Jr., a citizen of the United States, and a resident of the city of New York, borough of Manhattan, in the county and State of New York, have invented a new, original, and ornamental Design for a Cup, reference being had to the accompanying drawings.

Figure 1 is a front elevation of a cup, showing my design. Fig. 2 is a side elevation, and Fig. 3 is a plan.

What I claim as new, and desire to secure by Letters Patent, is—

The ornamental design for a cup, as shown.

JACOB A. MOLLER, Jr.
